UNITED STATES PATENT OFFICE.

FRANK C. DE REAMER, OF BRIDGEPORT, CONNECTICUT, ASSIGNOR TO GENERAL ELECTRIC COMPANY, A CORPORATION OF NEW YORK.

PUSH-BUTTON SWITCH.

Application filed October 7, 1924. Serial No. 742,237.

The present invention relates to electric house wiring devices and more especially to push button switches for making and breaking the electric circuit in incandescent lamp 5 sockets and similar devices.

In small electrical apparatus like lamp sockets, the space given up to the switch structure is so limited that the parts thereof must be few in number and that the making 10 and breaking of the circuit take place between parts moving with a spring action entirely independent of the hand-operated part. As a consequence of these limitations, the sockets having push button switch move- 15 ments heretofore on the market have been provided with movable pole pieces and stationary contacts that made only surface or touching contact when in closed position, which, as is well known, is liable to offer re- 20 sistance to the flow of current, causing heating and injury of the switch parts. The use of wedging or rubbing contacts in such sockets has not been heretofore found practical for the reason that the degree of friction be- 25 tween the rubbing contacts sometimes becomes too great or the strength of the spring too weak for proper separation of the parts when the hand-operated part is moved to effect opening of the switch.

30 The object of my invention is the provision of an improved push button switch adapted for incorporation in lamp sockets and other small devices which shall have high current interrupting capacity, which 35 shall consist of few and sturdy parts and which shall be of low cost to manufacture.

One embodiment of the invention is shown 40 in the accompanying drawing, in which Fig. 1 is a vertical section of the interior structure of an incandescent lamp socket; Fig. 2 is a top plan view of the base and switch parts, and Fig. 3 is a perspective view of the principal parts disassembled.

The socket interior shown has an insulating base 1 of porcelain or other insulating material with its outer wall generally cylindrical and its ends plane surfaces, in the upper of which is formed a transverse slot 2 for the reception of the switch mechanism, over which is a disk 3 of insulating material, such as indurated fibre or reinforced compound and the usual screw shell 4 for the reception of an end of an incandescent lamp and attached to the base 1 by 55 screws passing upwardly through holes 5

in the latter and holes 6 in the disk 3 and engaging tapped holes in a horseshoe-shaped part 7 overlying an inturned flange 8 of the screw shell 4, the latter being provided with a binding post 9 for connection with a line 60 wire.

The transverse slot 2 of the base has semi-cylindrical end portions 10 with transverse walls 11 between them and the center of the base. Vertical ways 12 are formed in the side walls of the slot 2 on opposite sides of the center of the base and a guide groove 13 extends down through the transverse walls 11 and nearly to the bottom end of the base.

The actuating member of the switch is a 70 V-shaped metal slide 14 with push buttons 15 attached in alignment to the opposite legs 16 thereof. When assembled in the base the lower edge of the V-shaped slide 14 will be received in the guide groove 13 75 and be free to move longitudinally therein, while the upper ends of the legs 16 will contact with the under surface of the insulating disk 3 and the push buttons be disposed in the cylindrical end portions 10 of 80 the main slot.

The movable pole piece 17 is a U-shaped metal punching with the ends 18 of its arms 19 turned outwardly to form pivots adapted to enter the vertical ways 12, while the main portion of the pole piece is free to move from against one transverse wall 11 to the other.

The elastic means for imparting snap movement to the movable pole piece 17 consists of a helical tensile spring 20 having its ends looped through holes 21 and 22 formed respectively in the inner central portions of the V-shaped actuator and the free end of the U-shaped pole piece. This arrangement of a tensile spring between the crossed actuator and pole piece tends to force the pivoted ends of the pole piece downwardly against the bottom ends of their ways 12 and the slide 14 upwardly with the ends of its spaced legs 16 against the smooth bearing surface of the insulating disk 3, and as a consequence substantially all friction between the slide and the porcelain base is avoided.

Upon moving the slide 14 back and forth in the guide groove 13, the lower end of the spring 20 is carried toward the pivotal axis of the pole piece 17, tensioning the spring and as the axis is passed the pole piece 110

swings over with a snap action under recoil of the spring. In case the pole piece should stick or for any reason fail to move after the lower end of the spring crosses its pivotal axis, the following leg 16 of the slide will engage the transverse portion of the pole piece and positively start it on its way.

The stationary contacts are phosphor bronze leaf springs 23 and 24 with inwardly inclined free ends adapted for rubbing contact with the pole piece 17 when the latter is moved to the left or on position. Contact spring 23 is provided at its rear end with an attachment lug 25 by which it is secured to the base by a rivet or screw passing through a hole 26, and extending from the outer end of the lug 25 is a center contact arm 27 which is folded over the insulating disk 3, the latter being peripherally notched at 28 for the reception of the same. Contact spring 24 is provided at its rear end with a folded over lug portion 29 for attachment to the base 1 by a screw or rivet in a hole 30 and extending downwardly from the outer end is a binding post 31 for the reception of the second line wire.

When the movable pole piece 17 is in the left or on position, current will flow from the line wire attached to binding post 31 to free end of the leaf spring contact 24, through the pole piece to the opposite leaf spring contact 23, through the latter and its integrally connected center contact arm 27, then through the lamp to the screw shell 4 and its binding post 9 to the second line wire.

While I have shown and described the best embodiment of the invention known to me, I do not desire to be restricted thereto.

40 What I claim as new and desire to secure by Letters Patent of the United States, is:—

1. A push button switch comprising an insulating base, an actuating slide mounted for longitudinal movement on said base and provided with spaced legs, a movable pole piece pivoted transversely of said slide and extending across the path of movement of

the said spaced legs to be engaged thereby in case of hanging at either end of its movement, and a tensile spring connected at its respective ends to said slide and said pole piece.

2. A push button switch comprising an insulating base provided with a guide groove, an actuating slide in said groove having spaced legs outside said groove, a U-shaped movable pole piece pivoted transversely of said groove with its free end in the path of movement of said legs to be engaged thereby in case of hanging at either end of its movement, and a tensile spring connected at its respective ends to said slide and said pole piece.

3. A push button switch comprising an insulating base provided with a transverse slot in one end thereof, leaf spring contacts secured to said base with the free ends thereof disposed on opposite sides of said slot, an actuating slide mounted for longitudinal movement in said slot and provided with spaced legs directed outwardly, a U-shaped movable pole piece pivoted at its lower end transversely of said slot and directed outwardly between said spaced legs, and a tensile spring having its ends respectively connected to said slide between said spaced legs and to the outer portion of said pole piece.

4. A push button switch comprising an insulating base provided with a transverse slot in one end thereof, an insulating disk secured to the slotted end of said base, an actuating slide mounted for longitudinal movement in said slot and provided with spaced legs adapted to engage the inner surface of said disk, a U-shaped movable pole piece pivoted at its ends in and transversely of said slot and its free end directed outwardly between said spaced legs, and a tensile spring having its ends respectively connected to said slide between said spaced legs and to the free end of said pole piece.

In witness whereof, I have hereunto set my hand this 25th day of September, 1924.

FRANK C. DE REAMER.
